By Attorney

INVENTOR

UNITED STATES PATENT OFFICE.

THEODORE F. TIMBY, OF ALMA, MICHIGAN.

CONVERTIBLE MACHINE-TOOL.

No. 836,154.

Specification of Letters Patent.

Patented Nov. 20, 1906.

Application filed February 6, 1904. Serial No. 192,442.

To all whom it may concern:

Be it known that I, THEODORE F. TIMBY, a citizen of the United States of America, and a resident of Alma, in the State of Michigan, 5 have invented a new and useful Improvement in Convertible Machine-Tools, of which the following is a specification.

This invention is primarily additional to the "Improvement in convertible machine-tools" that is the subject-matter of Letters Patent of the United States No. 701,424, granted to me the 3d of June, 1903.

The present invention may, however, be embodied in other convertible machine-tools 15 and other like tools wholly or in part of the vise type. The leading object of this invention is to facilitate taking apart and renewing the feed-screw device forming part of such tools.

20 The improvement consists in certain novel combinations of parts hereinafter described and claimed.

Two sheets of drawings accompany this specification as part thereof.

25 Figure 1 is a side view of the machine-tool as compacted for use as a vise or for shipment. Fig. 2 is an end view projected from Fig. 1. Fig. 3 is a side view of the machine-tool in full and dotted lines, illustrating its 30 use for drilling and for grinding purposes.

Fig. 4 represents a horizontal section on the line *a b*, Fig. 3. Fig. 5 represents a sectional side view of the anvil end of the machine-tool, with dotted lines illustrating the operation of a pipe-wrench device. Fig. 6 represents a plan view projected from Fig. 5 with the anvil-top removed. Fig. 7 is a bottom view of the anvil-top detached, and Fig. 8 is a perspective view of the nut of the feed-40 screw device.

Like reference letters and numbers indicate like parts in all the figures.

The anvil-base *a* and the movable main jaw *b* of the improved machine-tool are hollow steel castings with base portions 1 and 2, adapted to telescope or slide one within the other, and with lugs *c* on the base portion 1 of the anvil-base by which to attach the machine-tool to a bench or the like.

45 The anvil-top *d* is removable for the attachment in its place of a lathe back center or the like and is attached to the anvil-base *a* in the manner best shown by Figs. 5, 6, and 7, which see. For this purpose said anvil-base *a* has a flat top 4, provided in a central longitudinal line with notches *e* and *f*, the

former, *e*, undercut, which are snugly filled, respectively, by correspondingly-shaped lugs 5 and 6 on the bottom of the anvil-top *d* when the latter is in place, as in Fig. 5 and 60 in Figs. 1, 2, and 3. Owing to this simple construction, when the vise-jaws 7 and 8 are tightly closed, as in Fig. 1, it is impossible to remove or shake the anvil-top *d*, and pressure against the face of its vise-jaw 8, as in 65 the drilling operation, Fig. 3, tends to tighten it in place. When the vise-jaws 7 and 8 are separated, the anvil-top *d* may be freely lifted from its seat 4.

To provide for rigidly tightening the base 70 of the movable main jaw *b* within that of the anvil-base *a* at will in the several positions of the former, Figs. 1 and 3, and especially when the machine-tool is adjusted for use as an anvil or for shipment, Fig. 1, one side of 75 said base portion 1 of the anvil-base *a* is provided with a clamping device *g*, which may be in the form of a thumb-screw, as shown, impinging against the side of said base portion 2 of the movable main jaw *b*. For mov- 80 ing said parts *a* and *b* with reference to each other a longitudinal feed-screw *h*, Figs. 4 and 5, and a nut *i*, normally thereon, (shown detached by Fig. 8,) are so attached to the re- 85 spective parts as to facilitate fitting them and move particularly to facilitate removing them and renewing the nut *i*, which is the only part exposed to any considerable wear. The screw *h* has cylindrical portions 9 and 10 at its respective ends fitted to bearings in 90 the base portion 1 of the anvil-base *a*, and a circumferential groove 11, adjacent to the principal bearing 10, interlocks with a slotted slide 12, held in place within said base portion by a clamping-screw 13. When the 95 parts are in place, the screw is strongly supported at both ends. When the screw is disengaged from the nut *i* and said slide 12 is dropped, the screw may be readily with- 100 drawn by means of its hand-wheel 14. The 105 disengaged nut *i* drops from its place, being supported in working position, as best shown in Fig. 5, between vertical ribs 15, within the hollow base portion 2, and may be economically replaced by a new one when worn. The additional devices carried by said movable main jaw *b* include a rotatable horizontal spindle *j* at top immediately below the vise- 110 jaw 7 and provided with a chuck or chucks at 16 to carry interchangeably a drill-bit *k* or a grinding-wheel *l*, as represented by full and dotted lines in Fig. 3. The matching cham-

ber 17 to admit the point of the drill-bit is formed in the face of the anvil-top *d*, as shown in Fig. 5.

A hand-crank *m*, preferably provided with 5 a clamp-screw 18, may be applied directly to the protruding rear end of the spindle *j*, as shown in full lines in Fig. 3, for drilling purposes. Provision is made for driving said spindle *j* at different rates of speed by mounting beneath the spindle in the movable main jaw *b* two other short rotary shafts *n* and *o*, to either of which the crank *m* may be applied, and forming or making fast thereon and on said spindle *j* the successive wheels 15 and pinions 19, 20, 21, and 22 of a multiplying-train of spur-gearing. For the greatest speed suitable for the grinding operation the crank *m* is applied to the lower shaft *n*, as shown in dotted lines in Fig. 3. The middle shaft *o* provides for an intermediate rate of speed relative to that of the crank.

For greater speed or to utilize foot-power a wind-wheel or any convenient motor—a pulley *p*, Fig. 4—may be attached to either of the 25 shafts *n* or *o* or to the spindle *j*.

The lower shaft *n* is conveniently held in place against longitudinal displacement by a collar 23, Fig. 4, pinned thereto behind its principal bearing 24, and a supplemental 30 bearing 25 is conveniently formed behind the collar within the hollow base portion 2 of the movable main jaw. The middle shaft *o* may be held in place by the gearing or in any approved way.

35 The suitably-recessed upper portion of the anvil-base *a* conveniently accommodates a pipe-and-rod vise, as in previous forms of the machine-tool. For this purpose its sides are provided in the present device with holes *q*, 40 Figs. 1, 3, and 5, the reentrant inner ends of which form one jaw of a pair of maximum capacity. The other jaw *r* has a matching reentrant face of the same size and slides between the sides of the anvil-base under the 45 pressure of a hand-screw *s*, working in a nut portion 26 of the anvil-base beneath the anvil-horn 27. To economize time and labor in turning the screw *s*, the movable jaw *r* is made substantially L-shaped, as shown in 50 Fig. 5, and is reversible, as illustrated by full and dotted lines in that figure. For large pipes and rods the jaw *r* is used, as in full lines in Fig. 5, with its long heel 28, Fig. 5, within an opening immediately above said 55 nut portion 26. By reversing the jaw *r*, so that said long heel 28 is against the screw *s*, the device is quickly adapted to clamp the smallest pipes and rods with equally little manipulation of the screw. When there is 60 no pipe or rod between the jaws *q* and *r*, the movable jaw *r* can be removed from within the anvil-base at its inner end (shown at the right in Fig. 5) and inserted in reversed position. Owing to the location of the screw *s*, 65 the shouldered end of the jaw will contact

with the end of the screw in either of the two positions in which the jaw is shown by full and dotted lines in this figure, and without moving the screw the jaw may be thus quickly adjusted for large and small pipes or rods, and a comparatively limited rotation of this screw is consequently required in clamping 70 large and small pipes or rods.

A socket in the anvil-top *d* to receive a "hardy" and like attachments is shown at 29 75 Fig. 7. This device and other like details not essential to my respective claims hereto appended may be omitted, and other like modifications will suggest themselves to those skilled in the art.

Having thus described said improvement, I claim as my invention and desire to patent under this specification—

1. In combination, a base adapted to be fixedly attached to a bench or the like and 85 having an open-bottomed hollow base portion, a rotatable horizontal feed-screw mounted in said base portion, a renewable loose nut normally embracing said screw, and a movable main jaw having an open-bot- 90 tomed hollow base portion with vertical sides 95 slides within that of said base and constructed internally with vertical ribs on said vertical sides between which ribs said nut is inserted to attach said movable main 95 jaw to said nut, substantially as hereinbefore specified.

2. In combination, a base adapted to be fixedly attached to a bench or the like and 100 having an open-bottomed hollow base portion constructed internally with bearings for both ends of a rotatable horizontal screw, a feed-screw mounted in said bearings, means for rotating said screw, a renewable loose nut 105 normally embracing said screw between said bearings, and a movable main jaw having an open-bottomed hollow base portion with vertical sides 110 slides within that of said base and constructed internally with vertical ribs on said vertical sides between which ribs said 110 nut is inserted to attach said movable main 110 jaw to said nut, substantially as hereinbefore specified.

3. In combination, a base adapted to be fixedly attached to a bench or the like and 115 having an open-bottomed hollow base portion constructed internally with bearings for both ends of a rotatable horizontal screw, a superposed removable top piece having at 120 one end one of a pair of vise-jaws and at the other end an end extension of any required length and removable only when said jaws 125 are open, a feed-screw mounted in said bearings, a hand-wheel beneath said end extension for rotating said screw to open and close 125 said jaws, a renewable loose nut normally embracing said screw between said bearings, and a movable main jaw carrying the other 130 of said vise-jaws and having an open-bot- 130 tomed hollow base portion with vertical

sides slidable within that of said base and constructed internally with vertical ribs on said vertical sides between which ribs said nut is inserted to attach said movable main jaw thereto, substantially as hereinbefore specified.

4. In combination, a base adapted to be fixedly attached to a bench or the like and having an open-bottomed hollow base portion constructed internally with bearings for cylindrical portions at the respective ends of a rotatable horizontal screw, a feed-screw removably mounted in said bearings and constructed with such cylindrical portions one of which adjoins a circumferential groove in

20 said screw, a slide normally interlocked with said groove, means for rotating said screw, a renewable loose nut normally embracing said screw between said bearings, and a movable main jaw having an open-bottomed hollow base portion with vertical sides slidable within that of said base and constructed internally with vertical ribs on said vertical sides between which ribs said nut is inserted to attach said movable main jaw thereto, 25 substantially as hereinbefore specified.

THEODORE F. TIMBY.
